MACHINE FOR USE IN SETTING UP
CELLULAR CARTONSJames E. Annen and Alfred Conklin, Kalamazoo,
Mich., assignors to Sutherland Paper Company,
Kalamazoo, Mich., a corporation of Michigan

Application November 9, 1942, Serial No. 465,000

10 Claims. (Cl. 93—37)

This invention relates to improvements in machines for use in setting up cellular cartons.

The main objects of this invention are:

First, to provide a machine for use in setting up cellular cartons of the type having transverse partitions, the lower ends of which are disposed in slots in the bottom of the carton, which is simple and economical in structure and at the same time efficient in use.

Second, to provide a machine of the class described which is not likely to injure or distort the work.

Third, to provide a machine having the advantages above stated which requires little skill or effort on the part of the operator.

Further objects relating to details and economies of the invention will definitely appear from the description to follow. The invention is defined in the claims.

A structure which embodies the features of the invention is clearly illustrated in the accompanying drawings, in which:

Fig. 1 is a perspective view of a machine embodying the invention.

Fig. 2 is a fragmentary view partially in vertical longitudinal section.

Fig. 3 is a fragmentary view in transverse section on line 3—3 of Fig. 2.

Fig. 4 is an enlarged fragmentary view partially in longitudinal section illustrating the parts in a partially completed work stroke with a carton within the machine.

Fig. 5 is a similar fragmentary view in partial section showing the parts in completed work stroke position.

Fig. 6 is a fragmentary perspective view of a cellular carton in partially erected position ready for placing in the machine.

Fig. 7 is a fragmentary perspective view of the carton after the transverse partition members have been erected in the machine.

In the embodiment of the invention illustrated in the accompanying drawings the table 1 is provided with suitable supporting legs 2 supporting the table at suitable height for the convenience of the operator who stands or sits at the front of the table. Mounted centrally on the table is an upwardly facing tray-like holder 3 adapted to receive a partially erected cellular carton designated generally by the numeral 4 and to support it in upright position with the side walls erected. The sides 5 of the holder have upwardly diverging inner surfaces to support the upwardly diverging side walls 6 of the carton. The bottom members 7, 7 of the carton are inclined outwardly

and the bottom 8 of the holder is crowned or shaped to support these bottom sections as clearly shown in the drawings. The bottom of the holder has transverse upwardly facing grooves or slots 9 therein adapted to receive the lower ends 10 of the transverse partitions 11 when they are disposed through the slots 12 provided therefor in the bottom of the cartons, see Fig. 5.

In the steps of erecting the carton, when the side walls are brought to the position shown in Fig. 6 these transverse partition members 11 lie in an approximately horizontal plane, see Figs. 2 and 6. When the carton is placed within the holder its left hand end as viewed in Fig. 2 abuts the left hand end of the holder with the end cross portions 13 to which the end transverse partitions are hingedly connected in supported engagement with the ledges 14, see Fig. 2. As all of the transverse partition members are swung downwardly at one time considerable downward and endwise stress is applied, and these blocks sustain part of this stress.

Uprights 15 disposed at the ends of the holder have vertical slots 16 receiving the cross piece 17 at the upper ends of the slides 18. These slides are mounted in suitable slideways 19 provided in the housings 20 arranged on the outer sides of the uprights. The lower ends of these slides 18 are connected by a cross bar 21 to which the foot lever 22 is connected by means of the link 23 and the lever 24. When this foot lever or treadle is moved downwardly the slides are carried downwardly and consequently the cross bar 17 is carried downwardly, guided by the slots in the uprights. Return springs 25 are provided, only one of which is partially illustrated.

The erector member 26 is mounted on the bar 17 for longitudinal sliding or reciprocating movement thereon. This erector member is provided with transversely spaced longitudinal rows of downwardly projecting forwardly inclined fingers 27, there being a finger for each transverse partition element. On the work stroke the bar 17 with the erector member thereon is carried downwardly, the erector member is brought into engagement with the fixed downwardly inclined actuating cam 28 which imparts to the erector member a longitudinal movement as it completes the work stroke. This longitudinal movement, combined with the downward movement, effectively swings the partition elements into their erected position and snaps their lower ends through the slots in the bottom of the carton, the grooves 9 in the bottom of the holder permitting this action as clearly shown in Fig. 5.

The fingers are preferably shaped and positioned to slightly bend the partition elements when the erector is at the limit of its downward stroke, insuring that the partition elements are engaged in the slots in the carton bottom. On the return stroke the opposite end of the erector member comes into contact with the upwardly inclined return cam 29 which insures a reverse movement of the erector member and a withdrawal of the fingers from the carton without rupturing or straining the parts of the carton.

In use the operator partially erects the carton to the position shown in Fig. 6, places it in the holder, and actuates the foot lever 22. As the parts are automatically returned the operator can lift the completely erected carton from the holder. Comparatively little effort or skill is required in successfully operating the machine at quite high speed production.

No attempt has been made to illustrate or describe other embodiments or adaptations of the invention as it is believed this disclosure will enable those skilled in the art to adapt the invention as may be desired.

Having thus described the invention what is claimed as new and desired to secure by Letters Patent is:

1. In a machine of the class described, the combination of an upwardly facing tray-like holder adapted to receive a partially erected carton in upright position and comprising side walls and a crowned bottom provided with upwardly facing transverse longitudinally spaced grooves adapted to receive the lower ends of transverse partitions disposed through openings provided therefor in the bottom of a carton, vertically slotted uprights at the ends of said holder, vertically reciprocating slide members associated with said uprights, a cross bar disposed through said slots and connected to the upper ends of said slide members, an erector member longitudinally slidable on said cross bar and provided with transversely spaced longitudinal rows of downwardly projecting forwardly inclined fingers adapted to engage the transverse partitions of a carton, a downwardly inclined actuating cam disposed on the inner side of one of said uprights to be engaged by said erector member on the down stroke thereof for imparting longitudinal movement thereto on said cross bar, and an opposed upwardly inclined return cam on the inner side of the other upright acting to move the erector member longitudinally on said cross bar on its return stroke as the fingers thereof are withdrawn from an erected carton.

2. In a machine of the class described, the combination of an upwardly facing tray-like holder adapted to receive a partially erected carton in upright position, vertically slotted uprights at the ends of said holder, vertically reciprocating slide members associated with said uprights, a cross bar disposed through said slots and connected to the upper ends of said slide members, an erector member longitudinally slidable on said cross bar and provided with transversely spaced longitudinal rows of downwardly projecting fingers adapted to engage the transverse partitions of a carton, a downwardly inclined actuating cam disposed on the inner side of one of said uprights to be engaged by said erector member on the down stroke thereof for imparting longitudinal movement thereto on said cross bar, and an opposed upwardly inclined return cam on the inner side of the other upright acting to move the erector member longitudinally on said cross bar

on its return stroke as the fingers thereof are withdrawn from an erected carton.

3. In a machine of the class described, the combination of an upwardly facing holder adapted to receive a partially erected carton in upright position, vertically slotted uprights at the ends of said holder, vertically reciprocating slide members associated with said uprights, a cross bar disposed through said slots and connected to the upper ends of said slide members, an erector member longitudinally slidable on said cross bar and provided with transversely spaced longitudinal rows of downwardly projecting forwardly inclined partition engaging members, a downwardly inclined fixed actuating cam positioned to be engaged by said erector member on the down stroke thereof for actuating the same longitudinally on said cross bar, and an opposed oppositely inclined fixed cam positioned to be engaged by the erector member on its return stroke for actuating the same longitudinally on the withdrawal of the partition from the erected cartons.

4. In a machine of the class described, the combination of an upwardly facing holder adapted to receive a partially erected carton in upright position, uprights at the ends of said holder, vertically reciprocating slide members associated with said uprights, a cross bar connected to the upper ends of said slide members, an erector member longitudinally slidable on said cross bar and provided with downwardly projecting partition engaging members, a fixed actuating cam positioned to be engaged by said erector member on the down stroke thereof for actuating the same longitudinally on said cross bar, and an opposed fixed cam positioned to be engaged by the erector member on its return stroke for actuating the same longitudinally on the withdrawal of the fingers from the erected cartons.

5. In a machine of the class described, the combination of a holder adapted to receive a partially erected carton, an ejector member provided with transversely spaced longitudinal rows of downwardly projecting forwardly inclined partition engaging fingers, a reciprocating support on which said ejector member is mounted for longitudinal reciprocating movement, means for actuating said ejector support vertically to project the fingers of the ejector into a carton arranged in said holder for engagement with the transverse partitions of the carton, a downwardly inclined fixed actuating cam positioned to be engaged by the ejector member for actuating it on its support as it approaches the end of its down stroke, and an opposed upwardly inclined cam for actuating said ejector member longitudinally on its support at the beginning of the return stroke thereof.

6. In a machine of the class described, the combination of a holder adapted to receive a partially erected carton, an ejector member provided with transversely spaced downwardly projecting partition engaging fingers, a reciprocating support on which said ejector member is mounted for longitudinal reciprocating movement, means for actuating said ejector support to project the fingers of said ejector into a carton arranged in said holder for engagement with the transverse partitions of the carton, an actuating cam positioned to be engaged by the ejector member for actuating it longitudinally on its support as it approaches the end of its down stroke, and a return cam for actuating said

ejector member longitudinally on its support at the beginning of the return stroke thereof.

7. In a machine of the class described, the combination of an upwardly facing holder adapted to support a partially erected carton in upright position, uprights at the ends of said holder, vertically reciprocating slide members associated with said uprights, an ejector member supporting bar carried by said slide members, an ejector member slidably mounted on said bar and provided with downwardly projecting forwardly inclined partition engaging fingers, and cam means for imparting a longitudinal movement to said ejector member as it approaches the end of its work stroke and for imparting a reverse longitudinal movement thereto at the beginning of its return stroke.

8. In a machine of the class described, the combination of a holder adapted to support a partially erected carton in upright position, a vertically reciprocating support, an ejector member slidably mounted on said support and provided with projecting partition engaging fingers, and fixed cam means for imparting a longitudinal movement to said ejector member as it approaches the end of its work stroke and for imparting a reverse longitudinal movement thereto at the beginning of its return stroke.

9. In a machine of the class described, the

combination of an upwardly facing holder adapted to support a partially erected carton in position, a reciprocating ejector member support, an ejector member mounted for longitudinal movement on said support and provided with projecting partition engaging fingers, and cam means for imparting a longitudinal movement to said ejector member as it approaches the end of its work stroke and for imparting a reverse longitudinal movement thereto at the beginning of its return stroke.

10. In a machine of the class described, the combination of an upwardly facing holder adapted to support a partially erected carton 15, and provided at one end thereof with ledges adapted to receive the cross members to which the end transverse partition elements are connected, a reciprocating ejector member support, an erector member mounted for longitudinal movement on said support and provided with projecting partition engaging fingers, and means for imparting a longitudinal movement to said erector member as it approaches the end of its work stroke and for imparting a reverse longitudinal movement thereto at the beginning of its return stroke.
